UNITED STATES PATENT OFFICE.

FRANCIS W. PELOUBET, OF NEWARK, NEW JERSEY.

REED-ORGAN.

SPECIFICATION forming part of Letters Patent No. 301,000, dated June 24, 1884.

Application filed August 30, 1883. (No model.)

To all whom it may concern:

Be it known that I, FRANCIS W. PELOUBET, a citizen of the United States, residing at Newark, in the county of Essex and State of New Jersey, have invented certain new and useful Improvements in Reed-Organs; and I do hereby declare the following to be a full, clear, and exact description of the invention, such as will enable others skilled in the art to 5
10 which it appertains to make and use the same, reference being had to the accompanying drawings, and to letters of reference marked thereon, which form a part of this specification.

15 The object of this invention is to improve the quality of tone in reed-organs, to simplify the construction and action of the same, and to enable the various parts, and more especially the reeds, to be easily removed and 20 placed without disturbing the other parts.

The invention consists in such arrangement and combination of parts as will be hereinafter set forth and claimed.

In the drawings, in which similar letters of 25 reference indicate like parts in each of the figures, Figure 1 is a front elevation of a reed-organ action embodying my improvements. Fig. 2 is a side elevation of the same partly in 30 section, the section being taken through line α of Fig. 1; and Fig. 3 is an enlarged sectional view, showing the relation of the reed-chambers and the pallet to a draft-bellows.

In the drawings, A are the keys of the organ; B, the valves or palettes; C, the reed-board, and D the reeds. The reeds D are arranged in the reed-board one above the other, as shown, and are so placed that the reed-cell openings, which are covered by the valves, are in a direct line, preferably vertical, as 35 shown in Fig. 2; but they may be oblique, the inclination of the valve or palette conforming to the inclination or position of the openings of the reed-cells. The said reed-cells E open toward the front of the reed-board, as shown, 40 and through the opening the wind is drawn by suction-bellows P, Fig. 3. The reeds are placed at the bottom of said cells, the tongues of the reeds normally lying therein, and being drawn downward toward the resonating-

chambers F. Said resonating-chamber lying 50 beneath the reeds controls the vibration of the air after it passes through the reed-chamber and before entering into the wind-chest S. The resonating-chambers are supplied with valves G, to cut off the air passing therefrom. 55

In order to modify the quality of the tone, the air-chambers or resonating-chambers F may be made larger or smaller in size. The valves or palettes B are attached to the key-piece A' 60 by a pin, a , or any suitable device, at one end and to the stationary pieces b , by the pivoted strips c at the other. By this construction the palettes in rising under the influence of the keys have an oblique motion upward and 65 away from the openings of the reed-cells. The connectives c tend to steady the upper extremities of the palettes, and are adapted to throw said palettes farther, from the face of the reed-board than would the upward pivotal 70 motion of the portion a alone. This construction, therefore, by removing the palette farther from the reed-board, allows the air to be drawn into the reed-cells more freely with advantage to the resulting tone. Springs c' 75 are employed to return the palettes to their closed positions; but in lieu of them weights or other mechanical means or devices may be used. Openings of various forms, as H, Fig. 1, are made in the palettes, and are so placed 80 that when the palettes are raised the openings will be opposite to the cell-openings, and thus allow the removal and insertion of the reeds, which are constructed so as to slide into the cells without disturbing the valves or palettes. 85 In Fig. 2 the palette is shown raised with the openings therein opposite to the reed-cells.

In order to still further vary and improve the tone, one or more rows of reeds may be placed obliquely in the reed-board, similar to 90 the middle rows in Fig. 2, said reeds, whether arranged horizontally or obliquely within the reed-board, being so placed that the openings of the reed-cells, which are covered by the palettes, are in a direct line one above the 95 other either vertically or obliquely. While all the reed-cells are opened or uncovered at once by the lifting of the palettes, still the

passage of the air through certain sets of reeds is regulated by the valves G, which are connected with the stops and are manipulated by the player.

5 Many devices may be used to connect the pallet at the top to the reed-board or fixed portion of the organ, instead of the pivoted strip e; hence I do not wish to limit myself to the specific contrivance shown.

10 I am aware that it is not new to arrange cell-openings in a line to receive a palette, and such construction I do not claim; but

What I claim as new is—

15 1. The combination, in a reed-organ, of a reed-cell and a palette actuated by the key, and provided with an opening, through which the reed may be drawn, all substantially as herein set forth and shown.

20 2. The combination, in an organ, of a series of reed-cells arranged in a line with a palette

connected to the key or pieces A' at one end, and to a stationary piece or part at the other, said palette having an oblique movement, all substantially as and for the purposes set forth and shown.

25 3. The combination, with a series of cells and reeds, of a palette having an oblique movement to and from said series of reeds, and having a series of openings, through which the reeds may be drawn when the palette is open, substantially as herein set forth and shown.

30 In testimony that I claim the foregoing I have hereunto set my hand this 22d day of August, 1883.

FRANCIS W. PELOUBET.
